LOGGING TONGS

Stephen Kramer, Greenville, Calif.

Application March 15, 1949, Serial No. 81,434

2 Claims. (Cl. 294—100)

1

This invention relates to logging tongs and more particularly to means for clamping the tongs or hooks into secure engagement with a log and the like.

It is an object of this invention to provide logging tongs of the kind to be more particularly described hereinafter having a slip block on one end thereof so constructed and arranged relative to the hook members whereby a tension on the flexible member connecting the hook members together after a log has been engaged between the hook members will cause the hook members to clampingly engage the log engaged therewith.

Another object of this invention is to provide a device of this kind having a slip block so constructed and formed for sliding movement on a flexible member connecting a pair of long engaging hooks or tongs whereby sliding movement of the slip block on the looped flexible member toward the hooks or tongs after a log has been engaged therebetween the hooks or tongs will increase the pressure of engagement of the hooks or tongs on the engaged log and a tension on the looped flexible member will cause the hooks or tongs to clampingly engage the log held therebetween.

With the above and other objects in view, my invention consists in the arrangement, combination and the details of construction disclosed in the drawings and specification and then more particularly pointed out in the appended claims.

In the drawings:

Figure 1 is a side elevation of a pair of logging tongs, constructed according to an embodiment of my invention.

Figure 2 is a front elevation thereof.

Figure 3 is a vertical section through the slip block of the logging tongs, the slip block being removed from the assembly, taken on the line 3—3 of Figure 1.

Figure 4 is a bottom plan view of the slip block.

Figure 5 is a transverse section of the slip block, showing the engagement of the flexible member in the longitudinally extending passages.

Figure 6 is a fragmentary detail section taken on the line 6—6 of Figure 2.

Referring to the drawings, the numeral 10 designates generally a pair of tongs, constructed according to an embodiment of my invention, for dragging or snaking logs and the like. The tongs 10 are formed of a pair of hook members 11 and 12 connected together at one end by a flexible member 14. A slip block 15 is slidably engaged on the flexible member or cable 14 for drawing

2

the free ends of the hook members 11 and 12 together into secure clamping engagement with the logs.

The hooks 11 and 12 each comprise a shank portion 16 having an inturned bill 17 at one end thereof. The shanks 16 of the adjacent hooks 11 and 12 are disposed in spaced apart relation to each other along the length thereof and the bill sections 17 are disposed in confronting relation to each other. The terminal ends of the bills 17 are formed with flat points 18 which are adapted to penetrate the log or other article being dragged by tongs.

The upper end of the shanks 16 are flattened and formed with openings 19 through which the flexible member 14 is engaged for securing the ends of the flexible member to the adjacent hooks 11 and 12. The openings 19 are spaced apart along the length of the terminal end 20 of the shank 16 and a fastening element 21 engages through the lower end of the end section 20, adjacent the lowermost opening 19 for fixedly securing the end of the flexible member 14 to the hook.

The flexible member 14 is folded intermediate the length thereof to provide a pair of longitudinally extending adjacent stretches 22 and 23. The free ends of the reverted cable 14 are extended outwardly through the uppermost of the openings 19 and inwardly through the lowermost opening to be engaged with the fastening element 21 on the inside of the upper end of the shanks 16. The clamping elements 21 are formed with an apertured shank portion 24 and a threaded lug 25. The apertured shank portion 24 is adapted to be disposed on the inside of the hooks while the threaded lug 25 extends outwardly. A nut 26 engages on the lug 25 for drawing the clamping member 21 outwardly of the hook members. The terminal ends of the cable 14 are engaged through the aperture 27 of the shank portion 24 and tightening of the nuts 26 will clamp the free ends of the cable 14 against the inner side of the upper end 20 of the hook members 11 and 12.

The slip block 15 is slidably supported on the spaced stretches 22 and 23 of the flexible member or cable 14, the slip block being formed of a block of metal or body substantially U-shaped in configuration. The body 28 includes an upper bight portion 29 having a pair of depending side arms 30 and 31. A pair of plates 32 and 34 are fixed to, or preferably formed integral with the lower end of the side arms 30 and 31 to define a longitudinally extending passage 35 extending

from the lower end of the body 28 and terminating adjacent to and spaced from the upper end thereof.

A pin member is arranged transversely of and between and spaced from the side arms 30 and 31 adjacent the free ends thereof, the pin member embodying a pin 37 carrying a sleeve 36 fixedly connected to the side plates 32 and 34. The pin member separates the passage 35 into a pair of longitudinally extending openings 38 and 39 10 at the lower end of the body 28 and maintains the stretches 22, 23 out of engagement with each other.

The side arms 30 and 31 are formed with outwardly extending channels 40 and 41 adjacent 15 the upper ends thereof. The openings 40 and 41 converge downwardly in the body 28 in the direction of the lower end of the side arms 30 and 31 and the passage 35. The inner ends of the channels 40 and 41 communicate with the central opening 44 formed between the side arms 30 20 and 31 and the lower plates 32 and 34.

The bight portion 29, at the upper end of the body 28 is formed with a pair of upwardly converging arcuate grooves 45 and 46 on the opposite sides thereof. The lower or diverging ends of the grooves 45 and 46 communicate with the upper divergent ends of the openings or passages 40 and 41. The grooves 45 and 46 are defined on their front and rear sides by front and rear walls 47 and 48 respectively. As clearly noted in Figures 3 and 5 of the drawings, the surface of the block 15 at the upper end between the divergent ends of the grooves 45 and 46 is greater than the space between the inner surface of the side arms 30 and 31, at their lower ends. The channels 40 and 41 and the grooves 45 and 46 in the slip block 15 together form a pair of converging passages 49 and 50, the passages extending longitudinally inwardly from the face of the 40 bight portion 29 of the block 15 remote from the side arms 30 and 31 to and through the side arms 30 and 31 adjacent to and spaced from the face of the bight portion 29 contiguous to the side arms 30 and 31.

In use and operation of the logging tongs 10, the bills 17 of the hook members 11 and 12 are first placed in opposed engagement about a log, and the slip block 15 is then manually moved toward the shank 16 of the hook members 11 and 12 until the latter are under the desired pressure of engagement. At this point, a tension is exerted on the looped or connected ends of the cable 14, resulting in the hook members 11 and 12 to clampingly engage the log held therebetween and shift and deposit the log at the desired location. With the deposit of the log, tension on the looped end of the cable 14 is released, the slip

block 15 moved manually away from the hook members 11 and 12, and the bills 17 of the hook members 11 and 12 removed from the log.

I claim:

1. A log engaging device comprising a pair of confronting hook members each including an elongated shank and an inturned bill on one end thereof, a U-shaped slip block including a pair of spaced side arms and bight portion connecting said arms together at one end positioned adjacent to and spaced from the other ends of said shanks and having the free ends of the side arms facing and contiguous to said other ends of said shanks, there being a pair of converging passages in said slip block extending longitudinally inwardly from the face of said bight portion remote from said arms to and through said side arms adjacent to and spaced from the face of said bight portion contiguous to said arms, and a flexible member including spaced stretches, said stretches being slidably received in said passages and each having one end projecting beyond the free ends of the said side arms of said slip block and secured to the other end of the adjacent one of said shanks, the other ends of said stretches projecting beyond said bight portion of said slip block and secured together.

2. A log engaging device comprising a pair of confronting hook members each including an elongated shank and an inturned bill on one end thereof, a U-shaped slip block including a pair of spaced side arms and bight portion connecting said arms together at one end positioned adjacent to and spaced from the other ends of said shanks and having the free ends of the side arms facing and contiguous to the other ends of said shanks, there being a pair of converging passages in said slip block extending longitudinally inwardly from the face of said bight portion remote from said arms to and through said side arms adjacent to and spaced from the face of said bight portion contiguous to said arms, a flexible member including spaced stretches, said stretches being slidably received in said passages and each having one end projecting beyond the free ends of the said side arms of said slip block and secured to the other end of the adjacent one of said shanks, the other ends of said stretches projecting beyond said bight portion of said slip block and secured together, a pin member arranged transversely of and between and spaced from said side arms adjacent the free ends for maintaining said stretches out of engagement with each other, and means fixedly connecting said pin member to said side arms.

STEPHEN KRAMER.
